UNITED STATES PATENT OFFICE.

ANTHONY F. KOERBER, OF DETROIT, MICHIGAN.

CANDY-PULLING MACHINE.

1,096,728

Specification of Letters Patent. Patented May 12, 1914.

Application filed July 9, 1913. Serial No. 778,168.

To all whom it may concern:

Be it known that I, ANTHONY F. KOERBER, a citizen of the United States, residing at Detroit, in the county of Wayne and State 5 of Michigan, have invented new and useful Improvements in Candy-Pulling Machines, of which the following is a specification.

The invention relates to candy machines, and more particularly to the class of candy 10 pulling machines.

The primary object of the invention is the provision of a machine of this character wherein candy will be thoroughly worked and pulled during the continued operation 15 of the machine, thereby obviating the necessity of the hand pulling or working of the candy.

Another object of the invention is the provision of a machine of this character wherein 20 taffy candy will be thoroughly pulled for rendering it smooth and also to effect the bleaching thereof after the cooking process, thus obviating the hand working of the mass.

A further object of the invention is the provision of a machine of this character wherein the candy stuff will be thoroughly worked for rendering it light and brittle as well as obviating any possibility of the formation 25 of air cells within the stuff during the working of the same.

A still further object of the invention is the provision of a machine of this character which is simple in construction, reliable and efficient in operation, and inexpensive in manufacture.

With these and other objects in view, the invention consists in the construction, combination and arrangement of parts as will be 40 hereinafter fully described, illustrated in the accompanying drawing, and pointed out in the claims hereunto appended.

In the drawings: Figure 1 is a front elevation of a machine constructed in accordance with the invention. Fig. 2 is a side elevation thereof. Fig. 3 is a similar view looking toward the opposite side of the same. Fig. 4 is a vertical transverse sectional view through the machine. Fig. 5 is a sectional view on the line 5—5 of Fig. 1.

Similar reference characters indicate corresponding parts throughout the several views in the drawings.

Referring to the drawings by numerals, 55 the table 10, its legs 11 and the braces or hangers 12 constitute the framework of the

machine. Fixed to the longitudinal side edges of the table 10 are vertical uprights 13 and 14 respectively, whil mounted upon the inner face of the upright 14 is a bracket 15 60 which together with the said standard 14 forms a bearing for the axle portion 16 of a crank arm 17, the said axle portion 16 being fitted with a sprocket wheel 18 over which is trained an endless sprocket chain 19, the 65 same being also trained over a sprocket wheel 20 fixed to a driving shaft 21, the latter being journaled in hangers 22 fixed to and depending from the under side of the table 10, the said shaft being connected with 70 any suitable series of motive power for rotating the same.

Formed on the inner face of the upright 13 are inner and outer guideways 23 and 24 respectively, in which are slidably mounted 75 reciprocating bars 25, which have pivoted at their lower ends links 26, the same being loosely connected to oppositely disposed cranks 27 formed on the driving shaft 21 so that on the rotation of the latter the said 80 bars will be moved reversely with respect to each other for a purpose presently described.

Mounted in the bars 25 at their upper ends are pins or hooks 28 which are adapted to approach toward and recede from each other 85 on the reciprocation of the bars for pulling taffy candy when wrapped thereon. During the reciprocatory movement of the bars 25 the crank arm 17 revolves about the pins or hooks 28 for acting upon the candy stuff 90 when slack and also serves to pull the same while the machine is in operation. On the approach of the pins or hooks 28 toward each other the crank arm 17 revolves about the same, and as the said pins or hooks 28 95 separate by moving away from each other the said crank arm 17 passes between the same, thus constantly acting upon the candy during the pulling action by the pins on hooks 28, so that the candy stuff will be 100 thoroughly worked for bleaching the same and rendering it light and brittle. It is of course to be understood that the pins or hooks 28 and the crank arms 17 will be operated to travel in the path as heretofore 105 pointed out in any suitable manner, and also that the guide ways 23 and 24 may be arranged horizontally in contra-distinction to vertical or arranged angularly on the supporting frame. Furthermore the said 110 guideways may depend from the table 10 should it be desired.

From the foregoing it is thought that the construction and manner of operation of the device will be clearly understood, and therefore a more extended explanation has been

5 omitted.

What is claimed is:—

1. A machine of the class described comprising a supporting frame, spaced parallel supports carried by the frame at opposite sides thereof, guides formed on one of the supports, reciprocatingly movable members slidably held in the guides, a revolute member journaled in the other support, pulling arms on the respective members, and means

10 for simultaneously driving the said members whereby on movement of the pulling arms

on the reciprocating members inwardly and

outwardly toward and away from each other

the pulling arm on the revolute member

15 will make two complete revolutions.

2. A machine of the class described comprising a supporting frame, spaced parallel

supports carried by the frame at opposite sides thereof, guides formed on one of the supports, reciprocatingly movable members 25 slidably held in the guides, a revolute member journaled in the other support, pulling arms on the respective members, means for simultaneously driving the said members whereby on movement of the pulling arms 30 on the reciprocating members inwardly and outwardly toward and away from each other the pulling arm on the revolute member will make two complete revolutions, and means included in the driving means to act 35 upon the reciprocating members for moving the same in reverse directions to each other.

In testimony whereof I affix my signature in presence of two witnesses.

ANTHONY F. KOERBER.
